UNITED STATES PATENT OFFICE.

JOHN SCOTT AND JAMES A. McAVOY, OF WILLIMANTIC, CONNECTICUT.

SPINNING-FRAME.

SPECIFICATION forming part of Letters Patent No. 440,200, dated November 11, 1890.

Application filed June 22, 1888. Serial No. 277,925. (No model.)

To all whom it may concern:

Be it known that we, JOHN SCOTT and JAMES A. McAVOY, of Willimantic, in the county of Windham and State of Connecticut, have invented certain new and useful Improvements in Spinning-Frames, of which the following is a full, clear, and exact description, whereby any one skilled in the art can make and use the same.

10 Our improvement relates to the class of machines used in spinning yarn, thread, and the like; and our object is to provide an apparatus by means of which time and labor may be saved in the doffing of the spindles 15 after the bobbins borne by them have become filled.

To this end our improvement consists of a spinning-frame bearing a doffing-rod extending lengthwise of the frame in position to 20 raise and lower all of the guide-blocks along the frame at one time, in combination with the hinged guide-blocks; and it further consists in details of the several parts making up 25 the device and their combination, as more particularly hereinafter described, and pointed out in the claims.

Referring to the drawings, Figure 1 is a view in front elevation of part of a spinning-frame illustrating our invention. Fig. 2 is a 30 detail view, in cross-section, of the frame, showing parts in side elevation with the guide-blocks down. Fig. 3 is a like detail view, in vertical cross-section, of the frame, showing the guide-blocks lifted.

35 In the accompanying drawings, the letter *a* denotes the spinning-frame as a whole; *b*, the top rail; *c*, the ring-rail, and *d* the spindles, mounted and driven in the ordinary manner and supporting the usual bobbins. The 40 thread-guide *b* on the hinged block *b*' overhangs the spindle when the thread *e* is being spun in such manner that the guide must be lifted out of the way, as by throwing up the block, in order to place the bobbins on or to 45 remove them from the spindles. These blocks are usually thrown back one by one by the operative in doffing the spindles, and this takes considerable time. In any suitable position, preferably to the side parts of the 50 frame, I pivot the doffer-levers *f*, that support a doffer-rod *g*, that extends completely across the frame from side to side far enough

to underlie all of the hinged guide-blocks *b*'. This doffer-lever and its rod are preferably arranged as shown in the drawings, the rod 55 being borne on an outwardly-projecting arm *f*' of the lever and underneath the thread-guide and in front of a slug-hook *h*, the office of which is to catch and remove any bunch or slug that may be on the yarn as it is drawn 60 past the hook and onto the bobbin.

When the doffer-levers are lifted, as shown in Fig. 3 of the drawings, the rod lifts at once all of the guide-blocks and leaves the spindles along the whole length of the spinning-frame free, so that they may be all doffed and empty bobbins substituted. The guide-blocks are then returned to their proper position by simply pressing down on the doffer-levers, which throws the rod *g* against the projecting 70 arms of the slug-hooks and trips the blocks into proper position for the thread to be led through the guides and wound about the bobbins.

We claim as our invention—

1. In a spinning-frame, in combination with the hinged guide-blocks, the doffer-rod extending lengthwise of the frame and beneath the blocks, and the doffer-levers pivoted to the frame and secured to the rod, all substantially as described. 75

2. In a spinning-frame, in combination with the doffer-levers pivoted to the frame, the thread-guide blocks hinged to the frame and each having a downwardly-projecting part on 80 the under side, and the doffer-rod secured to the levers and extending lengthwise of the frame beneath the guide-blocks and in front of the downward projection on said blocks, all substantially as described. 85

3. In a spinning-frame, in combination with the doffer-levers pivoted to the frame, the guide-blocks hinged to the frame overhanging the spindle and each supporting a thread-guide and a downwardly-projecting slug-hook, 95 and the doffer-rod secured to the levers and extending lengthwise of the frame beneath the guide-blocks and in front of the slug-hook, all substantially as described. 90

JOHN SCOTT.
JAMES A. McAVOY.
